AUTOMATIC DAM

Henry D. Bentrup, Deerfield, Kans.

Application September 21, 1950, Serial No. 186,091

8 Claims. (Cl. 61—29)

The present invention relates to an automatic dam for use, for example, in irrigation ditches and the like, one of the important objects of the invention being to provide a more efficient and more easily operated device or assembly of this nature which provides for a more positive and reliable release of the stream-damming member or curtain to its operative position in a ditch at a predetermined time, and for the secured holding of the dam assembly in position in a ditch whereby leakage of and flow of water past the dam curtain is substantially eliminated.

Another important object of the present invention is to provide means in such a dam which holds the leading edge of the dam curtain on the ditch bottom and which also conforms the leading edge to any uneven places or irregular surfaces present in the ditch bottom.

Another important object of the invention is to provide a new and novel device of the aforesaid character which is relatively simple in the construction and association of its component parts whereby the device can be produced in a serviceable and attractive form at relatively low cost.

A further object of the present invention is to provide an improved dam assembly including a flexible curtain, having manually-set or adjusted means capable of automatically releasing the flexible curtain of the assembly at a predetermined time to permit it to move from its inoperative, or out-of-use position above the water level in the irrigation ditch, to its operative position within said ditch.

Other important objects and advantageous features of the invention will become apparent from the following description and the accompanying drawings, wherein, for purposes of illustration only, a specific embodiment of the invention is set forth in detail.

In the drawings, wherein like reference characters designate like parts throughout the several views:

Fig. 1 is a general top plan view showing the said embodiment in position relative to an irrigation ditch, and water distributing openings in the sides of the ditch above the dam;

Fig. 2 is a transverse vertical section taken on the line 2—2 of Fig. 1, looking in the direction of the arrows and showing the dam curtain in raised inoperative position;

Fig. 3 is an enlarged fragmentary vertical longitudinal section taken on the line 3—3 of Fig. 1, looking in the direction of the arrows and showing the dam curtain in elevated inoperative position in full lines, and in depressed operative position in broken lines;

Fig. 4 is an enlarged fragmentary perspective detail view, partly broken away, showing the set position of the dam curtain releasing means;

Fig. 5 is a view similar to Fig. 4 showing the curtain releasing means in released position;

Fig. 6 is an enlarged fragmentary perspective view of the clock operated mechanism, showing the same in engaged position; and

Fig. 7 is an enlarged transverse vertical sectional detail taken on the line 7—7 of Fig. 2.

Before explaining in detail the present invention it is to be understood that the invention is not limited in its application to the details of construction and arrangement of parts illustrated in the accompanying drawings, since the invention is capable of other embodiments and of being practiced or carried out in various ways. It is to be understood also that the phraseology or terminology employed herein is for the purpose of description and not of limitation, and it is not intended to limit the invention claimed herein beyond the requirements of the prior art.

Referring in detail to the drawings, the numeral 7

2

generally designates an irrigation ditch in which water 8 flows in the direction of the arrow 9 in Figures 1 and 3. As shown, the ditch 7 has flow openings 10 cut in its opposite banks 11 to a level below the top of the water 8, which are partially closed by light tampings of earth 12 positioned below the tops 13 of the banks 11 which are easily washed out by water from the ditch 7 upon a rise of the water 8 when the ditch 7 is dammed at a desired time at a point beyond the openings 10, so that water can flow through the cuts 10.

In accordance with the present invention such damming of the ditch 7 is automatically produced by placing across the ditch 7 on the downstream side of the cuts, a component A and below it a component B, the two components being operatively associated with a stream-damming member which may be in the form of a flexible curtain C positioned therebetween.

The component A, being the dam curtain releasing mechanism, preferably comprises a flat bar or plank 14 long enough to have adequate support on and extend between the ditch banks 11 and wide enough to eliminate sidewise tipping of the bar 14. A set of hinges 15 are positioned along the downstream edge 16 of the bar 14, each such hinge 15 involving a leaf 17 secured on the top of the bar 14, a leaf 18 secured to the side 19 of a substantially square release bar 20, with the pin barrels 21 and the cooperating hinge pin 22 extending over the edge 16, as shown in Figures 4 and 5. The hinges 15 are preferably of the spring type, with the coiled springs 23 thereof functioning to bias the bar 20 toward the depressed dam curtain releasing position, shown in Fig. 5, from the set dam curtain holding position, shown in Fig. 4.

The side of the bar 20 opposite the side 19 is formed with vertical sockets 28 spaced therealong in a longitudinal row. The leading edge 29 of the dam curtain C has fixed thereon at intervals corresponding in position to the sockets 28, the oval weights 30 which have stems 31 projecting therefrom. In the set position of the release bar 20 the weight stems 31 are loosely inserted in the sockets 28, as shown in Fig. 4, whereby the leading edge 29 of the dam curtain C is suspended in elevated inoperative position in the ditch 7 above the water 8, as shown in full lines in Fig. 3. The trailing edge 32 of the dam curtain C is secured in suitable manner to a bar 33 constituting the component B, and which straddles the ditch 7 at a suitable distance downstream from the component A. Adjustable and preferably double cords 34 are secured to opposite ends of the leading edge 29 of the dam curtain C by passing each of them through a grommet 29a (see Fig. 1). Knots 34a are then formed in the doubled cords. The knots are spaced, as shown, and are adapted to be engaged with hooks, or the like on the end portions of the bar 14. The doubled cords 34 preferably have enough slack to let the leading edge of the dam curtain reach the bottom 35 of the ditch 7, while controlling the position of the dam curtain. They permit the weights 30 to overcome floating tendencies of the dam curtain and to conform the leading edge 29 to any unevenness in the ditch bottom, thereby sealing off the flow of water past the dam curtain C. By providing the doubled cords 34 with the spaced knots 34a, it will be understood that the dam curtain can be adjusted properly for irrigation ditches, or the like of various depths, it being important, of course, that the leading or lower edge 29 of said flexible curtain lie against the bottom or bed of the ditch and conform to any irregularities in said bottom or ditch.

The release mechanism which in its set position holds the release bar in the position of Fig. 4 comprises a suitable clock mechanism such as an alarm clock 36, fixed on the top of the bar 14 behind the bar 20 and having an alarm winding key 37 projecting therefrom. As shown in Fig. 6, the key 37 has on one end a hook-like portion 38. This member or portion 38 may be attached to the key in any suitable manner, as by welding. A trigger rod 39 is loosely pivoted at one end on an eye 40 secured in the top of the bar 14, as indicated at 41, so that the rod 39 can lean at a forward angle 42 and engage its upper end 42 with the hook 38 and thereby be retained against falling in a forward and down-

ward direction when the key 37 is positioned with the hook 38 in a forward position, as shown in Fig. 6.

The trigger or trip rod 39 has an eye 43 near its upper end with which is connected the rearward end of a flexible cord or cable 44. The cord 44 is strung downwardly from the eye 43 and forwardly through an eye 45 fixed in the top of the bar 14 and forwardly at an upward angle, where its forward end is connected to an eye 46 fixed in the side 27 of the release bar 29, the length of the cord 44 being such that the release bar 29 is held in the set dam curtain retaining position of Fig. 4.

Assuming that the alarm mechanism (not shown) of the clock 36 has been wound and set to go "off" at a selected time, when it goes "off," the key 37 will be caused to rotate out of the set position at such time. In so doing, the key hook 38 moves away from the upper end of the rod 39. This frees the rod 39 and slackens the cord 44 so that the resistance to the springs 23 is removed and the springs 23 then act to overturn or swing the bar 29 forwardly and downwardly to the release position of Fig. 5, whereupon the weight stems 31 fall out of the sockets 28 and the leading edge 29 of the dam curtain C falls to the bottom 35 of the ditch 7 and dams the downstream flow of water therein. This causes the water 8 to rise behind the dam curtain C and wash out the fillings 12, thereby flowing water therethrough. A weather-proof box-like casing 47 may be provided to rest upon the bar 14 and enclose the clock 36 and trigger rod 39.

I claim:

1. In an automatic dam disposed in an irrigation ditch or the like, a flexible dam curtain having trailing and leading edges, a first support for the curtain comprising a bar to which the trailing edge of the curtain is attached straddling the irrigation ditch and resting upon its banks, a second supporting bar to which the leading edge of the curtain is attached straddling the irrigation ditch and resting upon its banks at points spaced from the first support, weight means attached to said leading edge for depressing said leading edge toward the ditch bottom when said edge is released from said second supporting bar, means hingedly attached to the second supporting bar and releasably connecting the weight means with said second supporting bar, and means carried by the second supporting bar for turning said hingedly attached means into position to release the weight means at a predetermined time to permit the weighted leading edge of the dam curtain to move into contact with the ditch bottom.

2. Structure according to claim 1, wherein said second supporting bar is disposed upstream from said first support bar, and wherein spring-actuated hinge members interconnect the hingedly attached means and said second supporting bar.

3. A flexible automatically released dam curtain assembly for application to an irrigation ditch adapted to straddle the ditch and rest upon the opposite banks thereof, comprising a flexible curtain having trailing and leading edges and spaced support members to which the trailing and leading edges of the flexible curtain are attached, the leading edge of said curtain being releasably secured to its support member, weight members disposed at the leading edge of said curtain and means carried by the support for the leading edge of the curtain for releasing said leading edge at a predetermined time whereby to permit the weight members to lower the curtain and move said edge into contact with the bottom of the irrigation ditch to cause the damming of water therein.

4. An automatic dam assembly for use with an irrigation ditch, comprising a flexible dam curtain having trailing and leading edges, a ditch straddling member for supporting the trailing edge of said curtain with relation to the ditch, a second ditch straddling member for supporting the leading edge of the curtain with relation to the ditch and being spaced from the first-named ditch straddling member, a release bar carried by the ditch straddling member for the leading edge of the curtain, weight members carried by said leading curtain edge and being removably supported by the release bar, spring means associated with said release bar for moving said bar at a predetermined time to free the removably supported weights and the leading edge of the curtain, and release mechanism operatively connected to the release bar for releasing the same.

5. A stream-damming member normally supported

above the flow of the stream in an irrigation ditch and having leading and trailing edges, spaced supporting members spanning the ditch for supporting said edges of the stream-damming member, said supporting members being located at points remote from each other and being spaced apart a distance corresponding to approximately the length of the stream-damming member, automatically actuated means operatively connected to said stream-damming member and maintained upon one of the supporting members for lowering said stream-damming member into a depending position in the stream at a predetermined time, said automatically actuated means including a hingedly-mounted bar to which the leading edge of the stream-damming member is releasably attached, and mechanism for moving the hingedly-mounted bar into a position to free said leading edge.

6. A flexible stream-damming curtain normally supported about the flow of the stream in an irrigation ditch, spaced supporting members spanning the ditch for supporting the stream-damming curtain, said supporting members being located at points remote from each other, automatically actuated means operatively connected to said flexible curtain and carried by a supporting member for lowering said curtain into a depending position in the stream at a predetermined time, the lower edge of said curtain resting upon the bottom of the ditch, said automatically actuated means including a spring-controlled hingedly-mounted bar to which the lower edge of the curtain is releasably attached, and mechanism for moving the spring-controlled hingedly-mounted bar into a position to free said lower edge.

7. The combination with an irrigation ditch having banks, of a dam comprising a flexible dam curtain having a trailing edge and a leading edge, a first bar-like support member straddling the ditch and resting upon the banks to which the trailing edge of the curtain is secured, a second support member straddling the ditch and spaced upstream from said first bar-like support member, weight means attached to the leading edge of said curtain for carrying the leading edge of the curtain to the bottom of the ditch when released from an elevated position, and releasing mechanism on said second support member comprising means to which said leading edge is releasably connected, said means occupying a set position in which said leading edge is supported in an elevated position and being adapted to occupy another position in which said leading edge is freed to enable said weight means to carry the leading edge of the dam curtain to the bottom of the ditch.

8. The combination with an irrigation ditch having banks, of a dam comprising a flexible dam curtain having a leading edge and a trailing edge, a first support straddling the ditch and resting upon the banks to which the trailing edge of the curtain is secured, a second support straddling the ditch and spaced upstream from said first support, weight means on the leading edge of said curtain arranged to carry the leading edge of the curtain to the bottom of the ditch when released from an elevated position, releasing mechanism on said second support comprising a member to which said leading edge is releasably connected, said member being arranged to occupy a set position in which said leading edge is supported in an elevated position and to occupy another position on which said leading edge is freed to enable said weight means to carry the leading edge of the dam curtain to the bottom of the ditch, said member comprising a bar swingably connected to said second support and having means for releasable engagement by said weight means, clock-controlled trigger means operatively attached to said swingably connected bar for holding said bar in set position for release upon the expiration of a predetermined period of time and arranged to free said bar for movement thereafter to its release position, and spring-hinge means for swingably interconnecting and acting between said second support and said bar for moving said bar into its release position.
